UNITED STATES PATENT OFFICE.

WILLIAM ERNST, OF RACINE, WISCONSIN, ASSIGNOR TO HAMILTON BEACH MFG. CO., OF RACINE, WISCONSIN, A CORPORATION OF WISCONSIN.

MOTOR MOUNTING.

Application filed May 5, 1926. Serial No. 106,977.

This invention relates to improvements in motor mountings, particularly adapted for the attachment of flat type electric motors to sewing machine heads.

5 It is one of the objects of the present invention to provide a motor mounting whereby an electric motor is yieldingly secured to the head of a sewing machine with its pulley wheel in frictional engagement with the 10 sewing machine hand wheel to propel the same.

A further object of the invention is to provide a spring actuated motor mounting of the class described arranged so that the 15 mounting and motor may be flexed away from the hand wheel to disengage the motor pulley wheel therefrom.

20 A further object of the invention is to provide a motor mounting of the class described constructed so that it may be yieldingly locked in any flexed position.

25 A further object of the invention is to provide a motor mounting of the class described in which the tightness of the engagement between the motor pulley wheel and the hand wheel may be readily manually adjusted.

30 A further object of the invention is to provide a motor mounting for sewing machine heads which is of very simple construction, is strong and durable, is inexpensive to manufacture, is easily installed, and is well adapted for the purposes described.

35 With the above and other objects in view the invention consists of the improved motor mounting for sewing machine heads, and its parts and combinations as set forth in the claims and all equivalents thereof.

40 In the accompanying drawing in which the same reference characters indicate the same parts in all of the views:

45 Fig. 1 is an end view of a sewing machine head provided with the improved motor mounting and motor carried thereby, part being broken away and shown in section;

Fig. 2 is a side view of the head showing the mounting and motor; and

50 Fig. 3 is a fragmentary view similar to Fig. 1 showing details of construction.

55 Referring now more particularly to the drawing it will appear that the numeral 5 indicates the head portion of a sewing machine carrying a revoluble hand wheel 6.

Secured to the lower flanged portion 7 of the side of the head is a flat spring steel

bracket 8, shaped as shown in Fig. 2. A flat type electric motor 9 is fastened to the medial portion of the bracket by screws 10 and in the normal position of said bracket the pulley wheel 11 of the motor is in yielding frictional engagement with the hand wheel 6 to drive the same. 60

The upper portion of the bracket member is formed with a vertical slot 12 through which the shank portion of an adjusting screw 13 extends. The end portion of the screw is threaded and enters an internally threaded bore 14 formed in the head. Coiled about the shank of the screw is a spring 15 and the same is confined between the screw head and the outer surface of the bracket. 65

The natural tendency of the spring bracket member is to flex away from sewing machine head and when it is desired to disengage the motor pulley wheel from the machine hand wheel it is only necessary to unthread the screw 13 a requisite amount and the bracket member will flex outwardly, as shown in Fig. 3. The provision of the vertical slot 12 in the upper portion of the 70 bracket permits the bracket to move on the screw shank without binding. Also, when the bracket is adjusted so that the motor is in normal engaging position, the coiled spring 15 allows it to yield slightly to compensate for irregularities in the rotation of the hand wheel. 75

80 From the foregoing description it will be seen that the improved motor mounting for sewing machine heads is of very simple and 85 novel construction, and is well adapted for the purposes set forth.

What is claimed as the invention is:

1. The combination with a sewing machine head having a hand wheel, of a motor mounting, comprising a yieldable member attached at an upper point and at a lower point to said head, and a motor carried by said yieldable member and normally maintained thereby in engagement with said 95 hand wheel. 100

2. The combination with a sewing machine head having a hand wheel, of a motor mounting, comprising a yieldable member rigidly secured at one portion to the head 105 and laterally movably adjustably secured at another portion to said head, and a motor carried by said yieldable member and normally maintained thereby in removable engagement with said hand wheel. 110

3. The combination with a sewing machine head having a hand wheel, of a motor mounting, comprising an elongated spring plate member rigidly secured at one end portion to the head and laterally movably adjustably secured at the other end portion to said head, and a motor carried by said spring plate member and normally maintained thereby in removable engagement with said hand wheel.

4. The combination with a sewing machine head having a hand wheel, of a motor mounting, comprising an elongated vertical spring plate member rigidly secured at its lower end portion to the head and laterally movably adjustably secured at its upper end portion to the head, and a motor carried by an intermediate portion of the spring plate member and normally maintained thereby in removable engagement with said hand wheel.

5. A motor mounting for sewing machine heads, comprising a springable motor carrying bracket member attachable to a sewing machine head, and means carried by the bracket member and engageable with the head for adjusting the amount of spring movement of the bracket member with respect to the head.

30 6. In combination, a sewing machine head revolvably carrying a hand wheel, an elongated flat spring steel bracket member se-

cured at its lower end portion to the side of said head and extending upwardly vertically, an electric motor secured to the medial portion of the bracket member, the pulley wheel of the same being adapted for frictional engagement with said hand wheel, the upper portion of the bracket member being formed with a vertical slot, an adjusting screw extending through said slot and entering the head, and a spring coiled about said screw and confined between the bracket member and the head of the screw.

7. The combination with a sewing machine head having a hand wheel, of a motor mounting, comprising a yieldable member rigidly secured at one portion to said head and yieldingly secured at another portion to said head, and a motor carried by said yieldable member and normally maintained thereby in engagement with said hand wheel.

8. The combination with a sewing machine head having a hand wheel, of a motor mounting, comprising a yieldable member rigidly secured at its lower end portion to said head and yieldingly secured at its upper end portion to said head, and a motor carried by said yieldable member and normally maintained thereby in engagement with said hand wheel.

In testimony whereof, I affix my signature.

WILLIAM ERNST.
